UNITED STATES PATENT OFFICE.

ZIGMAN CHAPLICK, OF CHICAGO, ILLINOIS.

DESIGN FOR A SMOKING STAND.

Application filed May 31, 1929. Serial No. 31,480. Term of patent 7 years.

To all whom it may concern:

Be it known that I, ZIGMAN CHAPLICK, a citizen of the United States, residing at 3742 West 18th Street, Chicago, Illinois, have invented a new, original, and ornamental Design for a Smoking Stand, of which the following is a specification, reference being had to the accompanying drawing, forming part thereof.

In the drawings:

Fig. 1 is a front elevation view;

Fig. 2 is a plan view, and

Fig. 3 is a side view with the base portion broken away.

I claim:

The ornamental design for a smoking stand as shown.

ZIGMAN CHAPLICK.
